NATHANIEL M. AYCOCK, OF HOUSTON, TEXAS.

LUBRICATING DEVICE.

Specification of Letters Patent.

Patented Feb. 8, 1916.

1,170,726.

Application filed July 9, 1914. Serial No. 849,903.

To all whom it may concern:

Be it known that I, NATHANIEL M. AYCOCK, a citizen of the United States, residing at Houston, in the county of Harris and State of Texas, have invented certain new and useful Improvements in Lubricating Devices, of which the following is a specification.

This invention relates to a new and useful improvement in a lubricating device.

The object of the invention is to provide a device of the character described which is designed particularly to be used for the purpose of supplying a lubricant to the journal boxes of cars, particularly railway and street cars.

Another feature of the invention resides in the provision of a device of the character described whereby a fixed amount of the lubricant may be discharged into each journal box thereby preventing an over and consequent waste.

A further feature of the invention resides in the provision of a means for forcing the lubricant out of the device thereby facilitating the operation of applying the lubricant to the boxes.

With the above and other objects in view, the invention has particular relation to certain novel features of construction, operation and arrangement of parts, an example of which is given in this specification and illustrated in the accompanying drawings, wherein the figure is a sectional side elevation of the device.

Referring now more particularly to the drawing, wherein like numerals of reference designate similar parts in each of the figures, the numeral 1 designates an oil can which has the bottom 2, one side of said bottom having a depression or recess 3. The top of the can has an inwardly extending annular rim 4, said rim having a suitable orifice 5, surrounded by a bushing 6, which is fixed to the flange 4, and into which the plug 7, is threaded. When it is desired to fill the can this plug may be removed. The inner edge of the flange 4, is turned over and threaded and a circular top 8, is provided whose rim is turned downwardly and externally threaded so that said top may be screwed into the down-turned portion of the flange 4, and the can thus completely closed.

Centrally located in the can 1 and fixed to the bottom thereof, is the pump cylinder 9, in which the piston 10, reciprocates. This

piston is fixed to the lower end of the piston rod 11, which extends upwardly through the central orifice 12, of the top 8, and the upper end of the piston rod has fixed thereto a knob or grip 13. A flat bail 14, is provided which is fixed to the sides of the can in any well-known manner and the piston rod 11, extends up through an alined orifice in the top of said bail. A collar 15, is provided which extends through the orifice in said bail and has an annular flange which engages against the under side of said bail. The upper end of this collar carries the grip or handhold 16, which is fixed to said collar.

Fixed upon the piston 11, underneath the collar 15, is a flange 17, and interposed between said flange and the top 8, and surrounding the piston rod is a strong coil spring 18, which normally holds the piston rod and the piston elevated. Surrounding the orifice 12, is an upstanding funnel-shaped flange 19, which is provided to catch any oil that may follow the piston rod out of the can, and to direct said oil back into the can. The bottom of the pump cylinder is provided with inlet and outlet check valves numbered respectively 20 and 21 and arranged on opposite sides of said cylinder. The intake valve 20 controls an intake pipe 22, which leads into the pump cylinder 9, and this intake pipe is flared at its free end which is turned downwardly into the recess 3. The outlet valve controls the outlet pipe 24 which leads from said cylinder and passes up through the flange 4, said outlet pipe having the lock nut 25, screwed thereon to prevent any leakage from the can around said pipe. The numeral 26, refers to the outlet spout which is attached to the upper end of the pipe 24, by means of elbow 27. This spout may be formed into any shape so as to be suitable for applying a lubricant to any style of journal.

The upper end of the piston rod is outwardly threaded and is provided with two nuts 28, 28, which are threaded on said piston rod and which are intended to lock against one another. These nuts may be run up or down on said threaded section and the range of movement of the piston thus fixed and the amount of lubricant discharged with each stroke of the piston thus determined.

The operation of the device is as follows:—The can 1 is first filled with a lubricant. The resistance of the spring 18 oper-

ating against the flange 17, keeps the piston elevated and the cylinder 9, filled with lubricant. When it is desired to discharge the lubricant into a journal box the manipulator 5 may grasp the grip 16, with his fingers and force the knob 13, downwardly until the nuts 28, 28 engage against the grip 16. This will force the piston 10, downwardly in its cylinder, will close the valve 20, open the 10 valve 21 and drive the lubricant up through the pipe 24, and out through the spout 26. When the knob 13, is released, the spring 18, will operate to elevate the piston rod and piston which will close the valve 21 15 open the valve 20 and fill the cylinder 9 with lubricant through, the intake pipe 22. By reason of the fact that the free end of the intake pipe extends into the recess 3, said free end will be submerged in the lubricant until the can has become completely 20 empty.

While I have shown only one form of this device it is obvious that the mechanical structure thereof may be changed without 25 departing from the principle of the invention, and I hereby reserve the right to make such changes in the mechanical structure thereof as will not depart from the scope of the appended claim.

30 What I claim is:—
A device of the character described includ-

ing a container, a removable top therefor having a central orifice, a funnel shaped flange fixed to the top and surrounding said orifice, a bail fixed to the container and 35 having an orifice in alignment with the central orifice of the top, a cylinder within the container and fixed to the bottom thereof, a piston in said cylinder, a piston rod to the inner end of which the piston is 40 fixed and which extends out through said orifices, a knob fixed to the upper end of the rod, a resilient member surrounding said rod, one end of which is attached to the rod and the other end of 45 which rests against said top, a collar surrounding the rod one end of which is fixed to said bail, a grip fixed to the other end of said collar, a discharge spout leading 50 from said cylinder, an inlet spout leading into said cylinder and having its outer end flared and curved downwardly and means for controlling said discharge and inlet spout.

In testimony whereof I have signed my 55 name to this specification in the presence of two subscribing witnesses.

NATHANIEL M. AYCOCK.
